UNITED STATES PATENT OFFICE.

WILLIAM A. BREWER, OF PITTSBURGH, PENNSYLVANIA, ASSIGNOR, BY MESNE ASSIGNMENTS, TO P. H. MURPHY COMPANY, OF PARNASSUS, PENNSYLVANIA, A CORPORATION OF PENNSYLVANIA.

CAR-ROOF.

1,145,545.

Specification of Letters Patent.

Patented July 6, 1915.

Application filed March 20, 1913. Serial No. 755,609.

To all whom it may concern:

Be it known that I, WILLIAM A. BREWER, a citizen of the United States, and a resident of the city of Pittsburgh, in the county 5 of Allegheny and State of Pennsylvania, have invented a new and useful Improvement in Car-Roofs, of which the following is a specification.

This invention relates to car roofs and 10 more particularly to outside metal roofs.

It has for its principal objects to produce an improved roof comprising a plurality of metal sheets movably mounted on the substructure and having their marginal 15 portions arranged to coöperate with hollow metal seam caps so as to provide flexible waterproof seam joints; to provide novel means for securing the seam caps to the substructure; to provide an improved support for the running board saddles in conjunction with the seam caps; and to attain certain advantages which will hereinafter 20 more fully appear.

The invention consists in the parts and 25 in the arrangements and combinations of parts hereinafter described and claimed.

In the accompanying drawings, which 30 form part of this specification and wherein like symbols refer to like parts wherever they occur,—Figure 1 is a fragmentary side elevation of the top portion of a car, showing a seam cap and coöperating portions of roof sheets embodying the invention; Fig. 2 is a section, on an enlarged 35 scale, through a seam cap and adjoining portions of two roof sheets; Fig. 3 is a top plan view of the end portion of a seam cap detached. Fig. 4 is a section on or about the line 4—4 of Fig. 1; Fig. 5 is a transverse section through the roof in the region 40 of the ridge pole, the seam cap and running board saddle being shown partly in section and partly in elevation; Fig. 6 is a section through the seam cap and securing clip for 45 the running board saddle, detached; Fig. 7 is an inverted view of one of the securing members for the seam cap; Fig. 8 is a section on a line 8—8 of Fig. 7; Fig. 9 is a section through the roof in the region of the 50 eaves, showing a modification of the seam cap and roof sheets; Fig. 10 is a transverse section through the roof in the region of the ridge pole, showing the seam cap illustrated in Fig. 9; Fig. 11 is a section on the

line 11—11 of Fig. 10; Fig. 12 is a detail view of the securing member for the seam cap shown in Fig. 9; Fig. 13 is a section through the eaves portion of the roof, showing the seam cap and securing member therefor in section and also showing a further modification of the roof sheets; Fig. 14 is a section through the seam cap and adjoining portions of two roof sheets, showing a modification of the marginal formation of the roof sheets; Fig. 15 is an end view of a roofing sheet as illustrated in Fig. 9; and Fig. 16 is an end view of the roofing sheet shown in Fig. 13.

The roof sheets 1 are movably mounted on the wooden sheathing 2 of the substructure. 70 The substructure may comprise any suitable framing. As shown in the drawings, the framing includes side plates 3 and a ridge pole 4. The carlines or transverse frame members are omitted, as they form no part 75 of the present invention. The side sheathing 5 is fastened to the side plates, and over this sheathing is placed the usual eaves molding or fascia 6 for protecting the roof covering in case the car "side scrapes". 80 The roof sheets 1, as shown, extend transversely all the way across the car and terminate at or near the eaves, and the sheets may be adapted either for a peaked roof, as shown, or a curved arched or radial roof, 85 as desired. The ends of the sheets may be turned down over the eaves, or as shown in Figs. 1 and 4, the ends of the sheets may be turned back under the body and spaced therefrom, as at 7, so as to coöperate with 90 the rebent inner marginal portions 8 of eaves flashing strips 9 whose outer marginal portions are turned down against the side of the car, as at 10, and nailed thereto.

In Fig. 9 the eaves flashing 9^a has a rebent inner marginal portion 8, the arrangement being similar to the flashing 9 except that said flashing 9^a and its rebent portion 8^a is narrower. In both cases, the flashing rests on a rabbeted portion of the roof 100 sheathing 2. The roof sheets 1 shown in Fig. 9 merely have their end portions offset downward so as to provide a lip 11 which rests on said flashing 9^a between the eaves and the rebent portion 8^a. A still further 105 modification is shown in Fig. 13. The eaves flashing 9^b has its inner marginal portion inserted under the roof sheathing 2, which

latter terminates approximately flush with the outer face of the side plate 3. The top edges of the side sheathing 5 and the eaves molding 6 terminate on a line with the top 5 of the side plate. The ends of the roof sheets are flexible, and are bent down and out, as at 12, so as to provide a springy lip which rests on the flashing between the eaves and the end of the roof sheathing.

10 The side marginal portions of the roof sheets 1 are turned back over the body portion and may be either flanged upward as at 13, as shown more clearly in Figs. 2, 11 and 15, wherein the flange comprises the two 15 thicknesses of the metal pressed close together, or said two upstanding thicknesses of metal may be spread apart to provide a hollow upstanding rib 13^a whose outer wall is vertical and inner wall is inclined as 20 shown more clearly in Figs. 14 and 16. The extreme marginal portion 14 of the turned over portion of the roof sheet is bent upward and back over said turned over portion at an inclination, as shown by full lines 25 in Figs. 15 and 16 and by dotted lines in Figs. 2, 11 and 14, before the sheets are applied to the roof. These marginal flanges 14 are adapted to be bent down upon horizontal flanges 15 extending from the lower 30 edges of the side walls 16 of seam caps 17 which hold the roof sheets down and cooperate with the marginal portions of the sheets to make waterproof seams. The normal distance between the edge of the flanges 35 14 before they are bent down and the flanges 13 or ribs 13^a, as the case may be, is such that the flanges 15 of the seam caps may be readily dropped in place; and after the flanges 14 are bent down upon said flanges 40 15 of the seam caps when the sheets and seam caps have been assembled on the roof, the distance between the edges of said flanges 14 and the flanges 13 or ribs 13^a is such that the flanges 14 will still overlap 45 the flanges 15 of the seam cap if the roof sheet is moved until the flange 13 comes in contact with the adjacent side wall 16 of the seam cap. This arrangement allows considerable movement of the roof sheets to 50 compensate for the weaving and racking motion of the car substructure without nullifying the waterproof qualities of the seams.

The seam caps, like the roof sheets, extend continuously across the car. They may be 55 pressed out of a single sheet of metal. As shown in Figs. 1 to 6, inclusive, the seam caps are of inverted channel shape, having plain flat top walls and straight vertical side walls with marginal flanges. The ends 60 of the seam caps are formed by slitting the upper corners and turning the side wall portions inward so as to overlap each other, and then turning the top wall down over 65 said inturned side wall portions and riveting the parts together, as at 18. The down-

turned top wall is extended down beyond the end of the roof sheathing and into the rabbeted portion of the eaves molding or fascia, as at 19.

In Figs. 9 to 14, inclusive, the cross section of the seam cap is modified. In this case, the lower portions of the side walls are flared, as at 16^a, and the seam cap is deeper than the cap shown in Figs. 1 to 6, inclusive. So, too, the end formation of the 70 seam cap is somewhat different. Instead of slitting the cap and making the folds as shown in Figs. 1 to 6, inclusive, the metal is crimped and die-shaped, as at 20, the end of the seam cap extending down below the 75 eaves, as at 19^a.

The seam caps are supported on the roof sheathing by brackets or clips having key slots for the reception of fastening bolts which are secured through the substructure. 80 As shown in Figs. 1 to 8, inclusive, the seam caps are secured to U-shaped sheet metal clips 21 having marginal flanges 22 which are riveted to the top wall 17 of the seam cap. These clips are provided with 85 key slots 23 having enlargements 24 which are counterparts of the heads of fastening bolts 25, so that said bolts may be inserted in said slots by first passing the head of the bolt edgewise through the enlargement 24 90 and then turning the body of the bolt into the slot 23. After the bolts have been placed in the clips they are dropped down through holes provided therefor in the sheathing and side plates and ridge pole, 95 and at any other point on the substructure where the securing clips happen to be placed. In practice, three of the clips are ordinarily provided for each seam cap, one being located at the ridge and the two others 100 over the side plates. In some cases, however, more of the clips may be used at intervals throughout the length of the seam cap.

The supporting brackets 21^a shown in 110 Figs. 9 to 13, inclusive, may be of malleable castings. They have plate portions 22^a which are riveted to the top wall of the seam cap and a bottom plate portion provided with a slot 23^a adapted to receive the 115 fastening bolt 25.

In the case of a peaked roof, there is obviously a special supporting bracket or clip provided at the ridge so as to correspond to the inclination of the roof on opposite sides 120 of the ridge. As shown in Fig. 5, the sheet metal clip 21 is identical with the clips over the side plates except that the flanges 22 are bent down to correspond to the inclination of the top wall of the seam cap; and the 125 casting 21^a shown in Fig. 10 is also specially shaped.

By the construction and arrangement of the roofing sheets and seam caps herein set forth, the seam cap is securely fastened so 130

as to retain the roofing sheets yet the fastening is somewhat flexible and the roofing sheets are permitted considerable movement to compensate for the weaving and racking of the car. The peculiar seam arrangement afforded by the coöperating flanges or ribs 13 or 13^a, as the case may be, and the down-turned flanges or lips 14 which overhang the flanges 15 of the seam 5 caps, makes it practically impossible for water to percolate or be driven in under the seam cap. Any water which may enter under the flange or lip 14 will be readily conducted off through the space between the 10 end of the flange 15 of the seam cap and the bend at the base of the flange 14; and should any water be driven with such force that it will get under the flange 15 of the seam cap, it will be conducted off through the space between the flange 13 or rib 13^a, as the case 15 may be, and side wall 16 of the seam cap, as the area is considerably greater than the opening through which the water enters.

The running board saddles 26 are supported on the seam caps by U-shaped metal clips 27. The side portions of these clips are perforated, as at 28, to receive bolts 29 which are passed through horizontal holes in the running board saddles. The bottom 20 portions of the clips rest flatwise on the seam caps and are fastened by rivets 30. The same rivets may also be used to fasten supporting clips 31 located under the seam caps and resting on the roof sheathing. 25 The supporting clips 31, as shown in Figs. 5 and 6, are of inverted U-shape and have marginal flanges 32 which rest flatwise on the roof sheathing. By this arrangement, the running board saddles have a firm support and the seam caps are prevented from being crushed in, without taking from the desired flexibility of the roof structure.

Obviously, the construction and arrangement of the several parts admits of considerable modification without departing from the invention. Therefore, I do not wish to be limited to the specific construction and arrangement shown.

What I claim is:

50 1. In a car roof, the combination with the substructure, of metal roof sheets movably mounted on the substructure, said sheets extending transversely of the car and being spaced apart, and inverted channel-shaped seam caps having flanged marginal portions straddling the adjacent marginal portions of adjoining sheets, said roof sheets having upstanding ribs at their margins within said seam caps and having flanges 55 outside of said seam caps turned down upon the marginal flanges of the latter.

2. In a car roof, the combination with the substructure, of metal roof sheets movably mounted on the substructure, said 60 sheets extending transversely of the car and

being spaced apart, and inverted channel-shaped seam caps having flanged marginal portions straddling the adjacent marginal portions of adjoining roof sheets, said roof sheets having their marginal portions folded back upon the top thereof, said folded marginal portions of the sheets being formed to provide upstanding ribs within said seam caps, and the extreme marginal portions of the folded portions of the sheets 70 outside of the seam caps being bent back upon the seam cap flanges. 75

3. In a car roof, the combination with the substructure, of metal roof sheets movably mounted on the substructure, said sheets extending transversely of the car and being spaced apart, and inverted channel-shaped seam caps having flanged marginal portions straddling the adjacent marginal portions of adjoining roof sheets, said roof 80 sheets having their marginal portions folded back upon the top thereof, said folded marginal portions of the sheets being formed to provide upstanding ribs within said seam caps, said ribs being spaced from the side 85 walls of said seam caps, and the extreme marginal portions of said folded portions of the sheets outside of the seam caps being bent back upon the seam cap flanges, the edges of said bent back extreme marginal 90 portions of the sheets being spaced from the adjacent side walls of the seam caps and the edges of the seam cap flanges being spaced from the bends at the bases of said bent back extreme marginal portions of the 95 sheets. 100

4. In a car roof, the combination with the substructure, said substructure including wooden sheathing terminating short of the eaves, of metal roof sheets movably mounted on the sheathing, said sheets extending transversely of the car and having their adjacent marginal portions arranged and adapted for a flexible waterproof seam, said sheets terminating short of the eaves and 105 having their end portions bent down and outward beyond the ends of the sheathing, and flashing strips extending underneath the end portions of the sheets in contact therewith, the inner marginal portions of 110 said flashing strips being inserted under the roof sheathing and the outer marginal portions being turned down over the eaves and secured to the side of the car. 115

5. In a car roof, metal roof sheets mounted on the substructure, said sheets extending transversely of the car and having upstanding ribs at their side margins and a flange inward from each marginal rib, said inner flanges being originally set toward the respective marginal ribs at an acute angle to the body of the sheet and adapted to be bent down parallel with the body of the sheet after the sheet is applied on the roof. 120 125

6. A metal roof sheet, having its side mar- 130

- ginal portions folded back upon it, said folded portions being formed to provide up-standing ribs at the margins of the sheet, the extreme marginal portions of said folded 5 portions of the sheet being bent upward and toward the marginal rib at an acute angle to the body of the sheet and adapted to be bent down parallel with the body of the sheet after the sheet is applied on the roof.
- 10 7. In a car roof, the combination with the substructure, of metal roof sheets mounted thereon, said roof sheets extending transversely of the car and being spaced apart, inverted channel-shaped seam caps extending 15 continuously across the car from eaves to eaves and respectively straddling the adjacent marginal portions of two roof sheets, the marginal portions of said seam caps cooperating with the adjacent portions of the 20 roof sheets to provide waterproof seams, securing brackets fastened to the seam caps and resting on the substructure between the adjacent marginal portions of the roof sheets, securing bolts fastened to said securing 25 brackets and fastened in the roof substructure, substantially U-shaped clips fastened on top of said seam caps, running board saddles secured to said clips by horizontal bolts extending through perforations 30 in the side members of said clips, and supporting brackets secured to the underside of the top walls of said seam caps beneath said U-shaped running board saddle supporting 35 clips and resting on the substructure.
8. In a car roof, the combination with the substructure, of metal roof sheets mounted thereon, said roof sheets extending transversely of the car and being spaced apart, inverted channel-shaped seam caps respec-
- tively straddling the adjacent marginal portions of two adjoining roof sheets, said seam caps extending continuously across the car from eaves to eaves and being supported at the middle and adjacent to the eaves by brackets resting on the substructure between 45 the adjacent faces of the roof sheets, securing bolts below said seam caps and fastened to said seam cap supporting brackets and fastened in the substructure, additional supporting brackets located under the seam caps 50 and resting on the substructure between the roof sheets, and running board saddles supported on said seam caps above said last-mentioned supporting brackets.
9. A seam cover for a car roof, said seam 55 cover being of inverted channel shape and having a sheet metal fastener secured at its ends to the under side of said seam cover between and spaced from its side walls, said fastener having an intermediate portion 60 spaced below said seam cover and provided with a key slot adapted to receive the head of a securing bolt.
10. A seam cover for a car roof, said seam 65 cover being of inverted channel shape and having a fastener secured to its under side between and spaced from its side walls, said fastener having a bearing portion spaced below said seam cover a distance greater 70 than the depth of the channel, and a slot in said fastener adapted to receive the head of a securing bolt.

Signed at Pittsburgh, Pennsylvania, this 17 day of March, 1913.

WILLIAM A. BREWER.
